UNITED STATES PATENT OFFICE

2,444,044

IMPULSE GENERATOR

Horace Edward Hopley, Liverpool, England, assignor, by mesne assignments, to Automatic Electric Laboratories, Inc., Chicago, Ill., a corporation of Delaware

Application July 17, 1942, Serial No. 451,283
In Great Britain September 13, 1941

1 Claim. (Cl. 175—373)

1

The present invention relates to impulse generators suitable for use in automatic telephone exchanges and is more particularly concerned with the provision of simple and compact arrangements for furnishing impulses of different speeds and ratios.

In large automatic exchanges a considerable number of testing devices of the type usually known as routiners may be involved, and it is economically practicable to provide a common motor-driven generator which is operated from the exchange battery and which is provided with a plurality of cam-operated impulsing contacts giving the various impulsing speeds and ratios required by the routiners.

In smaller exchanges, however, where only one or two routiners would be required the cost of providing a standard motor-driven impulse generator for their use may be so heavy as to make the installation of routiners an uneconomic proposition though it may be highly desirable from a maintenance standpoint. One of the chief objects of the invention is accordingly to provide a simple, cheap and reliable impulse generator suitable for use in conjunction with one or more routiners in an automatic exchange, whereby the cost of installing routiners and associated equipment is reduced to a figure which makes their use economically practicable in smaller exchanges than hitherto.

According to one feature of the invention an impulse generator suitable for use in a telephone exchange is arranged so that alternating current is applied to a gas discharge tube of the type which after it has struck remains conducting until the voltage applied to its anode circuit is reduced to substantially zero, the circuit of the tube including also an electromagnet which is operated from the time the applied alternating current voltage reaches the striking voltage until it is again reduced to zero and by its operation controls impulsing contacts.

According to another feature of the invention in an impulse generator suitable for use in a telephone exchange, an electromagnet is arranged to be energised and de-energised alternately for substantially equal intervals by the application of rectified alternating current of suitable voltage to the anode circuit of a grid controlled gas discharge tube, the electromagnet being also connected in the anode circuit and controlling suitable impulsing contacts.

The invention will be better understood from the following description of one method of carrying it into effect, reference being had to the ac-

2

companying drawing comprising Figs. 1 and 2. Fig. 1 is a circuit diagram showing how the output from a 16½ cycles per second ringing current generator of the type normally provided in an automatic telephone exchange is utilised to furnish impulses of different rates and ratios suitable for operating one or more automatic routining equipments provided in the exchange. Fig. 2 is a graphical timing diagram of the various relays employed and the circuits they control and serve to enable the operations of the circuits to be better appreciated.

The impulse generator comprises essentially the gas discharge tube or gas filled relay GDT, for instance of the mercury vapour type, the anode voltage of which is supplied by the exchange ringing current generator which connects with leads 10 and 11 and supplies current at a pressure of about 75 volts and a frequency of 16½ cycles per second. 20 The ringing current is applied to the full wave dry contact rectification arrangement FWR before connection to the tube GDT, and the anode circuit of the tube also includes the high speed relay P.

When the preliminary start contacts PS1 are 25 closed, the tube filament heating circuit is completed from the exchange battery via resistance YA, while the grid of the tube derives a potential from the potentiometer PR and thence via the high resistance YB, the grid potential being adjusted to a value such that the tube will only strike at substantially the peak value of the applied anode voltage.

Actual operation of the generator commences 30 when the start contacts S1, S2 and S3 are closed, the former contacts connecting the rectified ringing current voltage to the tube GDT and contacts S3 preparing locking and operating circuits for the pulse counting relays A—F.

Referring now to Fig. 2, the applied ringing current voltage curve at the top is shown for convenience as a triangular shaped wave and it will be seen that a complete cycle occupies 60 milliseconds. The output from the full wave rectifier FWR is shown directly beneath, from which it will be seen that voltage peaks occur every 30 milliseconds.

On the first peak of the applied voltage, tube GDT strikes and ionises in known manner, and thereupon remains in this condition until the anode voltage falls to substantially zero, after which it will not re-strike until the next peak voltage is reached. It will be seen that as a result the anode relay P will be operated as shown in the graphical diagram for the last half, i. e. 15 milliseconds of each 30 millisecond period, that is to

say $33\frac{1}{3}$ times per second with a 1:1 make to break ratio.

For the purpose of testing the automatic exchange apparatus the routiners mainly require loop impulses with the usual make to break ratio of 1:2 and preferably at a rate of 11-12 impulses per second, i. e. at a slightly higher speed than corresponds to a correctly-adjusted subscriber's dial, and other speeds and ratios may also be required. For this purpose the counting relays A-F are provided in association with relay P and function in the following manner to enable suitable impulses to be made available to the routiners.

On the first operation of relay P, relay A operates and at armature *a1* prepares an operating circuit for relay B. On the first release of relay P, the short-circuit is removed from relay B which operates in series with relay A which holds. On the second operation of relay P, earth extends over armatures *p1*, *d2* and *b2* to operate relay C and on the second release of relay P, relay D operates in series with relay C which holds, while relays A and B are released at armature *d1*. On the third operation of relay P, relay E operates and on the third release of relay P, relay F operates in series with relay E which holds, and relays C and D are released at armature *f1*. On the fourth operation of relay P, relay A re-operates and on the fourth release of relay P, relay B operates in series with relay A and relays F and E are released and the cycle of operations repeats itself as long as the conditions remain the same.

From Fig. 2 it will be seen that after the first operation of relay F, this relay is operated once every 90 milli-seconds and remains operated each time for a period of 30 milli-seconds. The make contact *f3* connected to circuit Y over leads 12 and 13 will therefore deliver pulses at the rate of $11\frac{1}{9}$ per second with the standard subscribers' dial make to break ratio of 1:2.

If pulses at the same rate but with a make to break ratio of 2:1 are required as in the case of impulses extending directly to switch driving magnets, these may be obtained by connecting normally made contacts of relay F in parallel with the normally open contact of relay B as shown by the armatures *f2* and *b3* which connect with circuit X over leads 14 and 15. Accordingly, since relay B is operated for 30 milli-seconds in each 90 milli-second period, and relay F is restored to normal immediately following the energization of relay B, remains unoperated for a period of 60 milli-seconds and then operates for a period of 30 milli-seconds, pulses at the rate of $11\frac{1}{9}$ impulses per second are generated having a make to break ratio of 2:1.

The same result could be obtained by omitting the armature *b3* and employing armature *f2* only to control the X circuit, or similar break armatures of relay B or relay D might be used to control the X circuit, but the use of the B relay make armature *b3* in association with the F relay break armature *f2* enables the wave form of the output impulses more nearly to approach the ideal, since X circuit is closed at *b3* at the same time that the circuit of relay F is opened by relay B. Similar arrangements might be applied in connection with the other pulsing out leads.

If a pulsing rate of the order of 22 impulses per second is required, that is to say with a cycle time of 45 milli-seconds, such as might be used

for relay timing purposes in the routiner, the combination of armatures *a2*, *c2* and *d3* which connect with circuit Z over leads 16 and 17 may be employed and it will be seen from Fig. 2 that impulses having a make to break ratio of 2:1 at a speed of approximately 22 impulses per second are produced.

Other combinations of armatures of relays A-F may also be employed to give the same or different sub-multiples of the basic pulsing rate of $33\frac{1}{3}$ impulses per second with different make to break ratios. As an alternative a small step-by-step electro-magnetically operated switch may be employed in place of the counting relays A-F, and it may be found satisfactory to include the magnet of the switch in the anode circuit of the tube GDT thereby enabling relay P to be dispensed with. The step-by-step switch might be provided with wipers and suitably strapped banks or alternatively it could be provided with sets of contacts operated from suitably shaped cams mounted on its driving shaft.

What I claim as new and desire to secure by Letters Patent is:

An impulse generator comprising a source of alternating current, a gaseous discharge tube including a cathode, an anode, and a control electrode, adjustable means for impressing a variable biasing potential between said control electrode and cathode, a quick-acting relay, means for energizing the anode-cathode path of said tube in series with said relay from said source, thereby causing at least one discharge to be initiated in said tube during each cycle of the alternating current wave when the anode-cathode potential rises to a critical value determined by the value of the biasing potential impressed on the control electrode thereof, each of the discharges being interrupted when the anode-cathode potential falls to a second critical value, said relay operated in response to each discharge of said tube, an impulsing circuit, and contacts controlled by said relay to produce periodic impulses, at a rate determined by the frequency of said source and at a break to make ratio determined by the adjustment of said first means, in said impulsing circuit.
